UNITED STATES PATENT OFFICE.

SIEM GROTH, OF DAYTON, TEXAS.

COLLAR BUTTON.

Application filed May 14, 1926. Serial No. 109,065.

My invention relates to buttons for shirt collars or the like, wherein a detachable button is inserted into a button hole upon the garment for use in buttoning the parts of the said garment together.

In the ordinary type of collar button, it is a well known fact that the buttons will not remain in place satisfactorily when the garment is unbuttoned. The result is that the buttons fall out, and are easily lost.

It is an object of the invention to provide a detachable button for collars, or for similar wearing apparel with means thereon to secure the button to the garment so that it cannot be accidentally removed and lost.

It is desired to provide an attaching means which can be readily adjusted to secure the button in place and which will not be noticeable when the article is being used.

Referring to the drawing herewith wherein a preferred embodiment of the invention is shown, Fig. 1 is a side view partly in section showing a button employing my invention, the device shown in connection with a section of garment. Fig. 2 is a side elevation taken at right angles to the view shown in Fig. 1. Fig. 3 is an elevation showing the button in detached position. Fig. 4 is a top plan view of the button as shown in Fig. 2. Like numerals of reference are employed to designate like parts in all the views.

The button upon which my improvement is connected may be made in various ways, and I have shown in the drawing a button having a circular base 1 with a central upright post 2 thereon, and a head 3 at the upper end of the post. I have shown the head as being approximately frusto-conical in shape, although its shape may be varied without departing from the spirit of the invention.

On the lower side of the head 3 at a point adjacent the post 2 I provide a recess 4 extending upwardly into the head from the lower side thereof. At the side of the base radially outward from the recess 4 in the head, I form a catch 5. Said catch is made of resilient metal, the lower edge being con-

nected with the margin of the base and bent inwardly and at an upward incline, as shown at 6, to a point adjacent the post, and is then directed upwardly along the side thereof so that the point 7 may be received within the recess 4 when the button is in latched position.

When using this button, the point 7 of the catch is bent downwardly and released from the head, as shown in Fig. 3. The head of the button is then inserted through the button hole, shown at 8 in Fig. 1, and the catch member is then bent inwardly above the band 9 of the shirt and is depressed so that the point 7 may come within the recess 4 of the head. The catch is then released so that it will assume the position shown in Fig. 1. It will be obvious that when the collar is attached to the button when in latched position, the presence of the catch or guard 5 will not be noticeable. It will, however, be impossible for the button to become loosened and lost even when the collar is unbuttoned.

When it is desired to remove the button, it is only necessary to depress the lower portion 6 of the catch member so as to remove the point 7 from the recess in the head of the button and allow it to be moved resiliently away from the head into the Fig. 3 position. The button may then be readily removed.

It is believed that the advantages of this device will be obvious to those skilled in the art, and while I have shown the invention as applied to a particular structure of button, it is to be understood that it is applicable to any ordinary type of collar button, or any button of similar nature, without departing from the spirit of the invention.

Having thus described my invention, what I claim as new and desire to protect by Letters Patent is:

1. In a button structure of the character described including a base member, a central post thereon and a head on said post, the combination of a catch member of resilient material secured to said base at the margin thereof and extended inwardly in spaced relation above said base, said catch member

2
having means thereon adapted to lie along said post and engage said head detachably in the manner described.

2. In a button structure of the character described including a circular base member, a central post on said base, the head on said post having a lower recess at one side thereof, a catch member on said base radially out-

ward from said recess, said catch member being of resilient material inclined upwardly to said post and having a point thereon adapted to resiliently engage within the said recess. 10

In testimony whereof I hereunto affix my signature this 8th day of May A. D. 1926.
